WIRE BASKET

James E. Myers, Niles, Mich., assignor to
Clark Equipment Company

Filed Mar. 21, 1972, Ser. No. 236,799

Term of patent 14 years

Int. Cl. D9—04

U.S. Cl. D9—247

FIG. 1

FIG. 2

FIG. 3

FIG. 4

FIG. 1 is a front perspective view of a wire basket showing my new design;

FIG. 2 is a front elevational view;

FIG. 3 is a side elevational view, the opposite side being a mirror image of the side shown; and

FIG. 4 is a bottom plan view thereof.

I claim:

The ornamental design for a wire basket, as shown and described.
